UNITED STATES PATENT OFFICE.

ALEXANDER RACK, OF PHILADELPHIA, PENNSYLVANIA.

SEWING-MACHINE BRAKE.

1,172,166.

Specification of Letters Patent. Patented Feb. 15, 1916.

Application filed April 13, 1915. Serial No. 21,042.

To all whom it may concern:

Be it known that I, ALEXANDER RACK, a subject of the Emperor of Austria-Hungary, residing at Philadelphia, in the county 5 of Philadelphia and State of Pennsylvania, have invented new and useful Improvements in Sewing-Machine Brakes, of which the following is a specification.

My invention relates to brakes and more 10 particularly to sewing machine brakes.

The object of the invention is to provide a device of the character described which will embody a brake shoe of such formation as to effectively grip the drive pulley and 15 thereby serve as a positive stop for the sewing machine.

Another object of the invention is to provide a brake that may be actuated by the operator's knee.

Another object of the invention is to provide a braking mechanism that is simple and efficient in construction and which may 20 be manufactured at a nominal cost.

In the accompanying drawings: Figure 25 1 is an elevation of my device showing it applied to a sewing machine. Fig. 2 is a transverse section of the brake taken through the line 2—2. Fig. 3 is a transverse section of the brake through the line 3—3 and showing the relative position of the brake shoe to the drive pulley.

Similar numbers designate corresponding parts in all of the views of the drawings.

Referring to the drawings, 1 is a sewing 35 machine including a work table 2 having depending bearings 3 secured to the under side thereof and adjacent opposite ends. A horizontal shaft 5 is journaled in the bearings 3 and is provided with a laterally extending crank arm 6 rigidly mounted on one end thereof, and an arcuate shaped crank arm 7 rigidly secured to the remaining end of the shaft 5 and extending in a direction opposite to the heretofore mentioned crank arm 6. This crank arm 7 has its lower extremity formed into a brake shoe 8 which is U-shaped in cross section and is adapted to straddle the periphery of the drive wheel 12 as shown.

Secured to the under side of the work table adjacent one end of the shaft 5 is a bracket 9 in which is pivotally mounted a bell crank lever comprising a substantially horizontal extension 10 adapted to engage the under side of the crank arm 6, and a vertical extension 11 which is widened

throughout a major portion of its length, as at 11' to provide a greater bearing surface.

Formed integrally with and extending upwardly from the bell crank lever at the juncture of the extension of said lever is a lug 13 adapted to engage the side of the bracket 9 when the bell crank is in inactive position. The crank arm 7 is connected to the under side of the work table by a coiled spring 14 which is adapted to exert its contractile force to disengage the brake shoe 8 from the drive pulley 12 and to restore the braking mechanism to its normal position.

From the foregoing construction it will be seen that when pressure is exerted upon the vertical extension 11 of the bell crank the horizontal extension 10 will be elevated, which in turn acting upon the crank arm 6 will cause a partial rotation of the shaft 5 moving the shoe 8 into engagement with the drive pulley 12 against the tension of the spring 14. It will be noticed that the parallel arms of the brake shoe 8 straddle the drive pulley when in active or inactive position, thereby preventing any longitudinal movement of the horizontal shaft 5 and insuring a proper engagement of the shoe with the pulley.

I claim:

1. In a sewing machine brake, the combination of bearings depending from the underside of the machine, a horizontal shaft journaled in said bearings, a crank arm secured to said shaft and lying in the same plane therewith, a second crank arm mounted on the remaining end of said shaft and extending in a direction opposite to the first mentioned crank arm, a shoe formed integral with the free end of the second mentioned crank arm and U-shaped in cross section, a bracket secured to the underside of the machine, a bell crank lever pivotedly mounted in said bracket and comprising a substantially horizontal extension and a vertical extension, said horizontal extension adapted to engage the underside of said first mentioned crank arm, and a coil spring having one end secured to the machine and the opposite end attached to the second mentioned crank arm intermediate its ends, said spring adapted to work in opposition to said bell crank.

2. In a sewing machine brake, the combination of bearings depending from the underside of the machine, a horizontal shaft

journalized in said bearings, a crank arm secured to said shaft and lying in the same plane therewith, a second crank arm mounted on the remaining end of said shaft and extending in a direction opposite to the first mentioned crank arm, a shoe formed integral with the free end of the second mentioned crank arm and U-shaped in cross section, a bracket secured to the underside of 10 the machine, a bell crank lever pivotedly mounted in said bracket and comprising a substantially horizontal extension and a vertical extension, said horizontal extension adapted to engage the underside of said first 15 mentioned crank arm, and a coil spring hav-

ing one end secured to the machine and the opposite end attached to the second mentioned crank arm intermediate its ends, said spring adapted to work in opposition to said bell crank, and a vertically extending lug 20 formed integral with said bell crank lever adjacent its pivot and adapted to normally engage one side of said bracket.

In testimony whereof I affix my signature in presence of two witnesses.

ALEXANDER RACK.

Witnesses:

HELEN G. DALEY,
W. S. McDOWELL.
